CLAIM

I claim the ornamental design for a nail clippings bag, as shown and described.

DESCRIPTION

FIG. 1 is a top plan view of a nail clippings bag.
FIG. 2 is a side view of a nail clippings bag, the opposite side being a mirror image thereof.
FIG. 3 is a rear view of a nail clippings bag.
FIG. 4 is a front view of a nail clippings bag.
FIG. 5 is a front and top perspective view of a nail clippings bag.
FIG. 6 is a rear and bottom perspective view of a nail clippings bag; and,
FIG. 7 is an additional front and top perspective view of a nail clippings bag.
